UNITED STATES PATENT OFFICE

ABRAHAM ROSENBAUM, OF BOSTON, MASSACHUSETTS

SAFETY RAZOR

Application filed August 1, 1931. Serial No. 554,413.

This invention relates to an improved safety razor, the object of the invention being primarily to have the clamp plate, guard plate and handle connected together when the razor blade is removed from the safety razor as well as when it is positioned therein, so that the blade can be removed and the other parts will be still connected together, and can be washed while connected together.

The invention consists in the combination and arrangement of parts set forth in the following specification and particularly as pointed out in the claim.

Referring to the drawing:—

Fig. 1 is a plan view of a safety razor embodying my invention.

Fig. 2 is a side elevation thereof.

Fig. 3 is a front elevation of the safety razor.

Fig. 4 is an enlarged sectional elevation taken on the line 4—4, Fig. 2, showing the clamp plate opened in dotted lines.

Fig. 5 is an underneath plan of the clamp plate.

Fig. 6 is a plan of the razor blade, and

Fig. 7 is a top plan of the guard plate.

Like numerals refer to like parts in the several views of the drawing.

In the drawing, 10 is the handle of the razor comprising a tube which has fast thereto at its outer end a cap 11. Within the tubular handle 10 a clamp screw 12 is rotatably mounted, the same being shouldered at its forward end at 13 and terminating at its forward end in a screw-threaded portion 14. At its rear end the clamp screw 12 terminates in a projection 15 which projects into a recess 16 in the cap 11 and is screw-threaded thereto, whereby the rear end of the clamp screw is guided and kept in alignment with the front end and also, when the clamp plate 23 is opened the clamp screw is held in the handle 10 in correct position to engage the clamp plate when it is closed. The clamp screw is provided with annular corrugated portions 29 and the handle 10 is provided with openings or slotted portions 30, so that the clamp screw can be rotated conveniently by the finger and thumb of the hand of the

user grasping the corrugated portions 29 through the openings 30.

The handle 10 is rigidly fastened to or made integral with a guard plate 17 provided with the usual serrations 18 on its opposite edges. The guard plate 17 has riveted thereto a pair of studs 19, and these studs project through a slot 20 in a razor blade 21 and into recesses 22 provided on the inner face of a clamp plate 23. The screw-threaded portion 14 of the clamp screw 12 extends through the guard plate 17 and also through the slot 20 in the razor blade 21 and into the clamp plate 23 with which it has screw-threaded engagement. The clamp plate 23 has a tongue 24 projecting from the inner face thereof and through a slot 25 in the razor blade 21 and also through a slot 26 in the guard plate 17. The tongue 24 has ears 27 projecting laterally therefrom and the tongue fits loosely in the slots 25 and 26 of the razor blade and guard plate respectively. The razor blade 21 is provided with a slot 25 at each of its opposite ends. The guard plate 17 is provided with a recess 28 at the end thereof opposite to the end in which the slot 26 is located, which allows the user of the razor to insert his finger therethrough and against the underside of the razor blade.

The general operation of the device hereinbefore specifically described is as follows:—Assuming the parts to be in the relative positions illustrated in Fig. 4, the user rotates the clamp screw 12 toward the left, thus disengaging the clamp plate therefrom and allowing it to be tipped upwardly at an angle, the same being hinged to the guard plate by the tongue 24. The ears 27 prevent the clamp plate from being tipped at too great an angle and also prevent it from being withdrawn from the guard plate.

When the clamp plate has been tipped at an angle as set forth, the razor can be moved longitudinally thereof to disengage it from the tongue 24, and the clamp screw portion 14 having been withdrawn sufficiently, the razor blade can be slipped entirely out of the razor from between the clamp plate and the guard plate. The razor blade can be

moved away from the guard plate by the finger or thumb of the user and the clamp plate can be also tipped at an angle, as aforesaid, the user inserting his thumb or finger through the recess 28 in the guard plate in order to press the razor blade and clamp plate away from the guard plate. A new razor blade can then be inserted by reversing the operation hereinbefore described.

10 More or less tension can be applied to the razor blade by screwing the clamp screw more or less as may be desired. The upper surface of the guard plate 17 is convex and the lower surface of the clamp plate 23 is concave, so that the razor when clamped assumes a concavo-convex form as illustrated in Fig. 2.

I claim:

20 A safety razor having, in combination, a guard plate, a clamp plate hinged thereto, a tubular handle provided with a slot and fast to the outer face of said guard plate, and a clamp screw rotatably mounted in the handle projecting through the guard plate and having screw-threaded engagement with the clamp plate whereby a razor blade may be clamped between the clamp and guard plates, said clamp screw also having screw-threaded engagement with said handle.

30 In testimony whereof I have hereunto set my hand.

ABRAHAM ROSENBAUM.
